DRAFT DEFLECTOR

Harry L. Smith, Minneapolis, Minn., assignor to
Smith System Heating Company, Minneapolis,
Minn., a corporation of Minnesota

Application January 9, 1935, Serial No. 982

1 Claim. (Cl. 98—99)

My invention provides an extremely simple and highly efficient window draft deflector for the ventilation of rooms of dwellings, office buildings, and the like, and generally stated, consists of the novel devices, combinations of devices and arrangement of parts hereinafter described and defined in the claim.

This improved ventilator is preferably made from sheet metal which may be provided with enamel or any other coating, preferably such as will harmonize with the painting or finish of the room to which it is to be applied. The ventilator is adjustable within a very large range of windows varying in width, is rigid, indestructible under ordinary use, may be very quickly assembled and applied to the window, and moreover, may be produced at comparatively low cost. It will not produce the glare produced by glass and is not breakable, as is glass.

A commercial form of the improved draft deflector or ventilator is illustrated in the accompanying drawing, wherein like characters indicate like parts throughout the several views.

Referring to the drawing:

Fig. 1 is a perspective taken from the inside of a room and showing a window to which the draft deflector is applied;

Fig. 2 is a horizontal section taken on the line 2—2 of Fig. 1;

Fig. 3 is a vertical section taken on the line 3—3 of Fig. 1;

Fig. 4 is a horizontal section corresponding to Fig. 2 but illustrating a slightly different way of applying the deflector to a window frame; and

Fig. 5 is a fragmentary plan view of one end of the deflector.

Referring first to the construction illustrated in Figs. 1, 2, and 3, the numeral 5 indicates the sill, the numeral 6 the window side frame, and the numeral 7 the lower sash of a window of ordinary construction. The numeral 8 indicates the inside stop strips of the side frames, and the numeral 9 indicates a handle applied to the lower edge of the sash 7. The draft deflector is made up of overlapping sheet metal plates 10 and end plates 11. The plates 10 are primarily made duplicates or facsimiles, that is, they are of the same vertical width and each is provided at one edge with a relatively narrow outturned flange 12 and at its other edge with a relatively wide U-shaped flange 13. On a particular plate, the flange 12 is turned in one direction and its flange 13 in the other direction. When these two plates are inverted, the narrow flanges 12 are slid telescopically into the wide or U-shaped flanges 13

of the companion plate, thereby making the shield longitudinally extensible and contractible to fit any window within quite a wide range of difference in width. After the two plates 10 have thus been made and flanged in exact duplicates, the outer end edges are turned laterally to form flanges 14, which flanges when the plates are telescoped together, will both project outward.

The end plates 11 are tapered in a downward direction and their inclined outer edges are bent to form U-shaped or channel flanges 15 into which the end flanges 14 of the two plates are adapted to be slid. The vertical inner edges of the end plates 11 are shown as provided with inturned anchoring flanges 16 that are perforated for the passage of screws therethrough. Also, the end plates adjacent to the flanges 16 are perforated to provide passages for screws 17 which, when applied as shown in Figs. 1 and 2, anchor the end plates directly to the inner faces of the inside stop strips 8. The structure illustrated in Fig. 4 is like that illustrated in Figs. 1, 2, and 3, except that the end plates are shown as anchored to the casing 8a by screws 17a passed through the perforations in the flanges 16.

The channel flanges 15 on the oblique edges of the end plates are open at their bottom, so that regardless of the exact adjustments of the said plates in their application to the window frames, the plates 10 will, under the action of gravity, slide downward until they rest in close engagement with the window sill. By reference to Fig. 3, it will be noted that the end plates have such width at their lower ends that the hand may freely reach the handle 9 of the sash, even when the sash is lowered. In Fig. 3, the window sash is shown as raised nearly to the top of the end plates, but, of course, the sash may be raised to any desired extent, which will give the proper ventilation without allowing the wind to blow horizontally into the room.

By reference to Fig. 5, it will be noted that the two plates 10, at their lower edges, are notched as shown at 10a. These notches cut short the bottom and end flanges of the respective plates and thus adapt the said plates to clear the in-turned flanges of the end plates 11. This permits the bottom flanges of the said plates always to rest closely in engagement with the sill 5. The flanges 12 and 13 reinforce and stiffen the plates 10. By reference to Fig. 2, it will be noted that the inner ends of said plates are slightly bent outward as shown at 10b so as to facilitate the telescoping of the flanges of the two plates. The angle made by plates 10 and their flanges 12 is 55

supplemental to the angle formed by 10 and 5, so that the lower surfaces of the flanges 12 and 13 will rest tightly against the sill 5 and exclude dust and water. The flanges 12 and 13 interlock in such a way as to give rigidity to the connected 5 sheets, making the same act substantially as a single but adjustable sheet. The plates, of course, may be quickly disconnected the one from the other and from the end plates.

From the foregoing, it is thought to be evident 10 that all of the advantages above generally set forth will be accomplished by this improved draft deflector or window ventilator. In commercial use, the device has been found highly satisfactory. It, of course, may be shipped in compact 15 form when the end plates are disconnected from the deflecting plates. The deflecting plates can be telescoped one upon the other so that they occupy only the length of one plate.

What I claim is:

20 A window draft deflector comprising a pair of

deflecting plates and a pair of end plates, said deflecting plates having upper and lower edge flanges slideable one within the other, and the outer ends of said deflecting plates and the inner edges of said end plates having flanges slideable 5 the one within the other, the inner edges of said end plates being oblique and tapering the end plates downwardly, and the sliding engagement between said end plates and deflecting plates permitting the latter to slide into contact with the 10 window sill, said deflecting plates having upper and lower edge flanges made in the same manner on both plates but with like flanges projecting in opposite directions, adapting the said sections, when inverted, to be telescoped one in respect to 15 the other and adapting the deflector to fit windows varying in width, the lower flanges of said plates being projected toward the interior of the room and away from the window.

HARRY L. SMITH. 20
